(57) **CLAIM**

The ornamental design for a faucet, as shown and described.

DESCRIPTION

FIG. 1 is a perspective view of the faucet;
FIG. 2 is a front view of the faucet;
FIG. 3 is a rear view of the faucet;
FIG. 4 is a left side view of the faucet; the right side view is a mirror image;
FIG. 5 is a top view of the faucet; and,
FIG. 6 is a bottom view of the faucet.
The broken lines are included for the purpose of illustrating the environmental structure and form no part of the claimed design.
